DANIEL J. DOUGHERTY, OF SNOHOMISH, WASHINGTON, ASSIGNOR OF ONE-THIRD TO
J. EDWARD GREGORSON, OF SEATTLE, WASHINGTON.

NAILING MACHINE FOR STRIP FLOORING.

Application filed March 23, 1927. Serial No. 177,677.

This invention relates to improvements in nailing machines and particularly to machines of a type designed for nailing hard wood flooring of that character that is not provided with the usual tongue and groove edges, but which is laid close and is nailed straight through from the top; such flooring is usually in strips about one-half inch thick and two inches wide and when laid the boards are placed and then wedged tightly together and held by a few nails, then, after the floor is completely laid, the nails are driven in, row after row; being spaced about one-fourth inch from the edges of the boards at each side.

It is the principal object of the present invention to provide a machine for nailing the boards after the flooring has been placed, and which will operate to advance automatically for proper spacing of the nails along a row; that is, with flooring two inches wide, after being properly positioned to drive a nail one-fourth inch from the edge of the first board, the machine will be automatically advanced, after that nail is driven, to a position for driving the next nail one-fourth inch from the opposite side edge of the board, then after that nail is driven it will advance onto the next board to drive the nail one-fourth inch from its edge, and so on down the row, moving first one and one-half inches and then one-half inch.

Other objects reside in the various details of construction and combination of parts as is hereinafter described and specifically pointed out in the claims terminating the specification.

In accomplishing these objects, I have provided the improved details of construction, the preferred forms of which are illustrated in the accompanying drawings, wherein—

Figure 1 is a side view, partly in vertical section, of a nailing machine embodied by this invention.

Figure 2 is a front view of the upper and lower portion of the same; one central portion being removed.

Figure 3 is a perspective view of the base portion of the device.

Figure 4 is a perspective view of the nail delivery slide.

Figure 5 is a perspective view of the advancing shoe.

Figure 6 is an enlarged section on line 55 6—6 in Figure 2.

Figure 7 is a perspective view of the advancing cam.

Referring more in detail to the drawings— 1 designates, in its entirety, the base portion 60 of the device. This comprises a vertically extending metallic block 1^a with a flat plate 1^b fixed to its lower end to extend rearwardly thereof with respect to the direction of movement of the machine during a nailing 65 operation. Fixed in the upper end of the block 1^a is a vertical tube 2 in which a plunger rod 3 is slidably contained and which, at its upper end, is equipped with a hand hold 4, in the form of a knob, whereby the plunger may be manually raised and then driven downwardly, and, at its lower end, has a nail driving pin 5, fixed therein by a set screw 6, which is adapted to drive the nails, as will presently be described. 75

Secured to the upper end of the tube 2 is a rearwardly diverted bracket 8 and revolvably contained therein is the upper end of a tube 9 which extends parallel with the tube 2 and which, at its lower end, has a rod 80 9' fixed therein as a continuation thereof which is contained revolvably within an opening 10 in a supporting bracket 11 that is fixed to the base member 1^a. Contained slidably within the upper end of the tube 9 is 85 a rod 12 provided with a spiral groove 13 into which a lug 14 formed in the side wall of the tube 9 is adapted to slide as a means of providing a connection whereby the tube will be caused to rotate when the rod 12 is 90 moved reciprocally therein. This rod 12 is extended rigidly to an arm 15 that is fixed to the upper end of the plunger rod 3; the connection providing that the rod 12 be moved upwardly and downwardly in accordance with movement of the plunger, and the groove 13 is so formed on the rod 12 that with each complete upward and downward reciprocal movement of the plunger, the tube 9 will be rotated one-half turn for-

ward and back. 95

Fixed in the outer end of bracket 8 is a horizontally extending shaft 18 and revoluble axially thereon is a nail container 19

of frustro-conical form provided with a door 20 that may be opened for filling the device with nails. Formed in the walls of the drum near its larger end are slots 21 through 5 which the nails may fall into a funnel-like receptacle 22 supported from the tube 2 for delivery through a tube 23 onto a nail slide 24 that is also fixed to the tube 2. This slide extends first downwardly and outwardly 10 and is then bent at a right angle and extends downwardly and inwardly to adjacent the upper end of a nail receiving opening 25 in the rear side of the base 1^a. This opening communicates with a vertical channel 26 15 through the base member 1^b. The two portions of the slide 24 are provided with longitudinally extending slots 26 and 26' which permit the passage therethrough of the nail shanks but not their head portions and the 20 lower end of slot 26 is provided with an enlargement 26^a through which the heads may pass to permit the nails to drop from the upper into the lower slot. Nails discharged from the funnel tube 13 head first are, by 25 this slide construction, reversed and delivered into the lower slide groove in proper position for nailing.

The nails as delivered into the slot of the lower slide are held against feeding into the 30 machine except as used, by a spring plate 28 that is fixed at one end by a screw 29 to the side of the base block 1^a and which has an inwardly turned finger 30 at its free end projecting into the path of the nails, as 35 shown in Figure 3. A short pin 31 is also slidably contained in a laterally opening hole 32 in the base block, and this engages, at its outer end, with the spring plate and, at its inner end, projects into the path of the 40 plunger 3 in such manner that, when the plunger is actuated downwardly, it presses the pin and spring plate outwardly sufficient to withdraw the finger 30 so that a single nail may feed into the opening 25 and will 45 be delivered into the channel 26 when the plunger and nail driving pin 5 are again lifted for the next driving operation. As the plunger is lifted, the pin 31 and finger move inwardly and the latter again holds back the nails in the delivery slide so that 50 they cannot flow freely into the opening 25.

The nail container 19 is provided at one 55 end with a ratchet wheel 35 adapted to be engaged by a pawl 36 at the outer end of a lever 37 that is pivotally mounted from the bracket arm 8 by a pin 38 with the inner end of the lever extended upwardly and inwardly to a position to be engaged by the handle member 4 with each downward, driving movement of the latter. This engagement of the handle piece with the lever rocks the latter to actuate the pawl and ratchet to revolve the drum 19 so that nails 60 will be fed from the latter into the funnel 65 22; thereby controlling the feed of the

nails so as to prevent clogging in the funnel.

The means provided for automatically advancing the device after each nailing operation consists of a pair of knurled advancing wheels 40-41 fastened on a shaft 42 supported by brackets 43 and 44 fixed to base block 1^a. A ratchet 45 is fixed on the end of the shaft adapted to be engaged and rotated by a hooked pawl 46 that is pivotally attached to one arm 47^a of a bell crank mounted by a pivot pin 48 on the bracket 44; the other arm 47^b of the bell crank is connected operatively to the lower end of a bar 49 that is slidably attached, by means of a collar 50 at its upper end, about the lower end 70 portion of the tube 9. Mounted on this slide bar 49 is a roller 51 and this operates in rolling contact with the edge of a circular cam 52 that is revoluble on the lower end of the rod 9' which is fixed in the lower end 80 of tube 9. The hub portion of this cam has a ratchet 53 adapted to be engaged by a ratchet collar 54 that is slidably keyed on the rod 9' and which is pressed against the ratchet 53 by a spring 55 so that with each 85 rotative movement of the tube 9 caused by lifting the nail driving plunger and rod 12 upwardly, the cam will be advanced rotatably one-half turn.

The cam 52 has two rises formed thereon 95 which are at diametrically opposite points, as designated at 52^a and 52^b; the rise 52^b being relatively high as compared to the other. This provides that the movement of the slide 49 when actuated by the higher 100 part 52^b of the cam will be greater than when actuated by the rise 52^a and the rotative movement of the knurled advancing wheels 40-41 produced through the bell crank, ratchet and pawl connection with the slide 105 49 is governed accordingly.

A bell crank 60 is also pivotally attached to the outer end of the bracket 11 and this has one arm attached operatively to the lower end of the slide 49 and its other arm pivotally connected with presser foot 62 that engages the floor as a means of supplementing the wheels 40-41 in advancing the device with each upward reciprocal movement of the slide; the distance of advancement being 115 in accordance with the movement of the slide as provided by the two rises in the cam. A spring 65 is fixed to an arm of the bell crank to bear against the foot to hold it in holding contact with the floor 120 and the foot has a plurality of pointed pins 67 thereon for engaging the floor to prevent slippage of the shoe when pressure is applied against it. Also, a set screw 68 is adjustably mounted in the bracket 11 to limit 125 the inward movement of the bell crank 60. A gauge bar 70 is pivotally attached to the base, as in Figure 2, with a marker 71 at its outer end, which is used as a means of 130 gauging the spacing of the rows of nails and

also to act as a guide whereby the operator may keep the rows straight.

Assuming the device to be so constructed, its operation is as follows:

- 5 With the device properly set for starting, at one edge of the board, the operator first actuates the plunger 3 downwardly to displace the finger 30 for the delivery of a nail from slide 24 into opening 25. He then 10 grasps the knob 4 and draws the plunger upwardly so that the nail drops into the channel 26. He then drives the plunger down so that the pin 5 at the lower end of the plunger drives the nail completely in. 15 The plunger is then again raised to its upper limit, thereby rotating the tube 9 and cam 52 so that the high rise 52^b of the cam will lift the slide 49 and actuate the bell cranks 47 and 60 to rotate the wheels 40 and 20 41 and also actuate the presser foot 62 against the floor to advance the machine, through the farther distance of travel as provided by the cam, so that it is in proper position for driving a nail in the opposite 25 edge of the board. The plunger is then driven downwardly to drive this nail, then as it is again raised, the cam is again rotatably advanced to cause the lower rise 52^a to actuate the slide 49 to effect the advancement 30 of the machine through its shorter distance of travel as provided by the cam so that the machine will be advanced onto the next board. Thus, the machine, as designed for two inch flooring boards, would be alternately 35 advanced one and one-half inches and then one-half inch so as to position it for driving the nails one-fourth inch from the edges of the boards. For boards of a different width, cams 52 with their rises properly 40 formed for the desired spacing of nails could be provided for interchangeable use on the rod 9'.

The machine as here shown is manually operated but it is apparent that it could be 45 operated mechanically by a motor.

Having thus described my invention, what I claim as new therein and desire to secure by Letters-Patent, is:

1. A nailing device of the character described, comprising a base member, nail feeding and driving means on the base member, and mechanism operable by successive resetting operations of the nail driving means for alternately advancing the machine through spacings of different length. 55
2. A device of the character described, comprising a base member having a nail guide channel and a lateral opening into the channel, a nail container, a nailing device 60 including a reciprocally movable plunger, means operable under control of the plunger for feeding nails from the container to the lateral openings, means operable by each retractive movement of the plunger for admitting 65 a single nail into the guide channel, an advancing means, and mechanism operatively connecting the advancing means with the plunger whereby successive retractive movements of the plunger will advance the machine through spacings of different length. 70
3. In a device of the character described, comprising a base member, nail feeding means mounted on the base, a nail driving means including a reciprocally movable plunger, an advancing means comprising a cam adapted to be rotatably advanced with each retractive movement of the plunger, and an advancing foot operatively connected for actuation by the cam to advance the machine between successive nailing positions. 75
4. In a device of the character described, comprising a base member, nail feeding means mounted on the base, a nail driving means including a reciprocally movable plunger, an advancing means comprising a cam adapted to be rotatably advanced with each retractive movement of the plunger, said means having rises of different height thereon, a cam follower, and a presser shoe 80 operatively connected with the follower and adapted to be actuated incidental to rotative movements of the cam to advance the machine through spacings of different length. 85
5. A nailing device of the character described, comprising a base member, a nailing device mounted on the base including a reciprocally mounted plunger, a nail feeding device operable under control of the plunger for feeding nails into position to be driven, a revolvably mounted tube, a rod reciprocally contained in the tube and connected with the plunger to be reciprocated therewith and having connection with the tube for rotating the latter incidental to reciprocation of the plunger and rod, a cam connected with the tube and adapted to be rotatably advanced with each retractive movement of the plunger, a bracket fixed to the base, a bell crank mounted on the bracket having a presser foot fixed to one end engageable with the floor and having a slide bar pivotally attached to its other end, and a roller on the slide bar engageable with the cam to actuate the bell crank and presser foot for advancing the machine with each 95 rotative movement of the cam. 100
6. A device as in claim 5, wherein the cam is provided with rises of different height whereby the machine will be advanced 105 through spacings of different length. 110
7. A nailing device of the character described, comprising a base member, a nailing device mounted on the base including a reciprocally mounted plunger, a nail feeding device operable under control of the plunger for feeding nails into position to be driven, a revolvably mounted tube, a rod reciprocally contained in the tube and connected with the plunger to be reciprocated 115 120 125 130

therewith and having connecting with the tube for rotating the latter incidental to reciprocation of the plunger and rod, a cam connected with the tube and adapted to be 5 rotatably advanced with each retractive movement of the plunger, a pair of advancing rollers attached to the base, a bell crank mounted on the base, a bar having sliding connection at one end with the tube and 10 pivotal connection at its other end with the bell crank, a presser foot connected with the other end of the bell crank for engaging the

floor and means operatively connecting the bell crank for rotating the advancing rollers, and a roller on the slide engageable with the 15 cam through which the slide will be actuated with each rotative movement of the cam to effect movement of the presser foot and advancing rollers whereby the machine will be advanced from one nailing position 20 to the next.

Signed at Everett, Washington, this 16 day of March, 1927.

DANIEL J. DOUGHERTY.
